GAME-BOARD OR TOY

Earle L. Whitehall, Kankakee, Ill.

Application March 29, 1935, Serial No. 13,715

4 Claims. (Cl. 273—91)

My present invention relates to a game or toy and it has particular reference to a game which simulates the well-known game of base-ball. The structure which I have devised for playing the game, while shown in connection with a base-ball field, is, of course, capable of adaptation to other games, such as foot-ball, golf, and the like where points are scored and penalties are imposed upon the players.

10 The playing board, to which my invention is more particularly directed, comprises an open box-like main body consisting of a rectangular bottom and upstanding sides, and spaced above the bottom is a second plate or false-bottom upon which a base-ball field is laid out, the different zones or areas thereon which provide the goals and penalties are designated by means of openings made in the upper plate. There is an entrance aperture upon the infield, at about the location of the pitcher's box, and there is a ramp that leads from the bottom of the box to an edge of the entrance aperture to provide egress for a ball with which the game is played.

15 The whole structure is tiltable so that the player may discharge the playing token or ball upon the infield, and then by giving a sudden tilt to the structure, in a different direction from the initial tilting, may direct the ball or token towards the goals. Practically all of the usual situations 20 occurring in a base-ball game may be played with the structure which I have devised.

25 The article is fabricated in a novel manner from sheet-metal so that there are practically no parts to get out of order, and the assembly of the parts, as well as the parts themselves, have been designed for economic manufacture so that the game may be sold for a moderate retail price. The structure is dependable and is sturdy in construction and provides a game that is entertaining, and may be played by any number of persons, either singly or in a group.

30 The structure of the game-board which I have devised is capable of embodiment in a small game board to be held in the hand while being played, or it may be enlarged to the size of a card table and mounted upon a suitable support or pedestal upon which it may be tilted during the playing of the game.

35 I prefer to practice my invention and obtain the advantages hereinbefore set forth by means of the structure now to be described and which is shown in the accompanying drawings.

In the drawings:—

40 Figure 1 is a top plan, drawn full size, of my game board made in the smaller hand variety.

45 Figure 2 is a plan showing details of the inclined ramp and its guard walls, the upper plate being removed for clearness and the view being fragmentary.

50 Figure 3 is a view, partly in section, on line 3—3 of Figure 1, showing the token or ball approaching the ramp.

55 Figure 4 is a view similar to Figure 3, showing the structure tilted in order to discharge the token or ball upon the playing field.

60 Figure 5 is an enlarged detail in vertical section showing the assembly of the ramp and guide-way.

65 Figure 6 is a vertical section, enlarged, through an edge of the playing board.

70 Figure 7 is a side view, on a greatly reduced scale, showing a larger size game-board that is mounted upon a pedestal or stand.

75 The drawings are to be understood as more or less schematic for the purpose of illustrating typical or preferred forms in which my invention may be made, and in these drawings, like reference characters designate like parts wherever such parts appear.

80 Referring more particularly to Figures 1 to 6, inclusive, it will be seen the structure comprises a bottom member 10, consisting of a rectangular metal plate having side walls 11 disposed laterally thereto so as to provide a shallow box-like body structure. About midway their height the side walls are bent inwardly as at 12 so that the upper portions of the walls incline slightly inwardly as shown. A horizontal plate 13 provides a false bottom for the box-like structure above mentioned that is spaced above the bottom 10 and has its edges bent upwardly inside and then downwardly outside the inclined upper portions of the walls 11 so that U-shaped members 14 are provided, the adjacent faces of which are pressed together with the walls 11 between them to provide a stable structure.

85 The plate 13 forming the false bottom has a base-ball infield and outfield represented thereon, as well as the usual foul lines. Beyond the three fielder's stations and adjacent the walls 11, are suitable goals or coveted areas which are shown herein as round holes 15, although it will be understood these goals may be shallow depressions made in the plate 13 to receive the ball.

90 These goals or coveted areas 15 have designations indicating the type of hit that has been secured by the player who has been acting as the batter. The holes 15, as will be seen in Figure 1, are graduated in size, from the largest or single base hit, to the smallest or home-run hit.

95 The fielder's stations are also goals or coveted

areas and are elliptical in outline and are in the form of elongated holes 16 formed in the plate 13, but may be in the form of shallow depressions. Adjacent the three bases and the short-stop are other goals or coveted areas which are in the form of elliptical holes 17 substantially of the same dimensions as the holes 16. The fielder's stations 16, the short stop and the basemen's stations 17 are designated as penalties. At the outer ends of 10 the foul lines there are holes 18 in the plate 13 which are likewise designated for penalties.

In the corner portions adjacent the home-plate is a penalty goal in the form of a round hole 19, designated as a "strike" and upon each side of the 15 hole 19 are round holes 20 that are designated as "balls".

The token or member with which the game is played is in the form of a metal ball, of a size permitting it to pass through the small holes 15 20 designated as home-runs or the small holes 20 designated as balls.

The token is deposited through any of the holes so that it will fall to the bottom of the box-like structure and the structure is then tilted so as to 25 discharge the token upon the infield. Skill is then required to tilt the board in a manner to direct the ball toward one of the scoring goals or coveted areas. The manner of playing the game is indicated schematically in Figures 3 and 4.

30 Provision is made for readily transferring the ball or token from the bottom to the upper plate. This is in the form of an entrance aperture 21 on the infield at about the location of the pitcher's box, and an upwardly inclined ramp 22 extending 35 from the bottom 10 to an edge of the entrance aperture 21. This ramp 22 is an elongated tapered tongue cut out of the plate forming the bottom 10, which tongue is bent upwardly oblique to the planes of the bottom and false-bottom as shown. 40 In order to close the open space thus made in the bottom, a keystone-shaped metal strip 23 is wedged at one end under the ramp and at its other end is secured in place by a tongue 24 stamped out of the bottom plate 10 as detailed in 45 Figures 2 to 5.

Guard walls 25 are disposed along each edge of the ramp and consist of an elongated metal strip of a width to fit between the bottom and the false-bottom or upper plate 13. This metal strip 50 is bent midway its end to provide the converging V-shaped guard walls 25 that flare away from each other beyond the ramp, and which, at their end nearest each other are connected by a transverse web or member 26 that is notched out in its 55 upper portion to provide a seat 27 on which the adjacent end portion of the ramp rests as shown in enlarged detail in Figure 5.

A lug 28, upturned from the closure strip 23, engages the lower portion of the web 26 below the 60 seat and aids in maintaining the before-mentioned parts in assembly. The plate 13 is provided with a shallow tapered channel 29 that extends from the edge of the entrance aperture 21 towards or to the home-plate (see Fig. 1), and 65 said channel becomes shallower as it approaches the home-plate. This channel 29 forms a continuation of the ramp 22 and directs the moving ball or token normally towards the holes 19 and 20 designated as "strike" and "ball", but it will be 70 understood that the player who is operating the game-board in the hands may quickly tilt the board to another plane after or while the ball is moving in the channel, thus causing the ball to be directed towards the goals or coveted areas 15, in 75 an attempt to secure hits or runs. Should the

ball, however, fall into any of the holes 16, 17 or 18, the player is penalized by an out.

If desired, the end of the ramp 22 next to or abutting the edge of entrance aperture 21 may be provided with a shouldered lip 30 that projects 5 under the adjacent edge of said opening, thus providing arrangement of a very sturdy construction that prevents the assembled elements becoming dislodged or separated from hard usage.

The structure which has been above described 10 and shown in Figures 1 to 6 inclusive, is of a size approximately that shown in Figures 1, 3, and 4 and is adapted to be used or held in the hands of the players so that it may be readily and quickly tilted in one direction or the other while playing 15 the game.

In Figure 7, however, the game-board, which is here designated as 31, is preferably a table top, approximately the size of a portable or foldable card-table. This board is mounted upon a base 20 32 of convex shape that is provided with a centrally disposed socket 33 to permit it to be readily mounted upon or dismounted from a pedestal 34 or other suitable support. The game-board 31 and the bottom member 32 may be placed upon any level surface and tilted upon the convex portion of the bottom. When mounted upon the pedestal 34, the latter is preferably provided with a flexible extension 35 that may be in the form 25 of a coiled or spiral spring so that it may be readily flexed in any direction when the player tilts the table top upon the pedestal.

It will be seen from the foregoing that the structure may be of a miniature size for use in 35 the hands of the players or may be either mounted upon the pedestal when played or may be removed from the pedestal and placed upon a library or dining room table. The principle of structure and arrangement and disposition of the parts of the game-board are substantially the same in 40 these several types.

What I claim is:—

1. A game or toy comprising a titlable structure 45 consisting of spaced superposed plates, side members extending upward and inward from the edges of said plates, and bounding a playing area on the upper plate, the side members of one plate being folded down over the side members of the other plate, said upper plate having a smooth 50 surface provided with a plurality of goals on the playing area and an entrance aperture, and means for guiding a spherical token from the lower plate and depositing it through said aperture upon the playing area where said token may be freely directed toward any goal by tilting the 55 entire structure.

2. A game or toy comprising a titlable structure 60 consisting of spaced superposed plates, side members extending upward and inward from the edges of said plates, and bounding a playing area on the upper plate, the side members of one plate being folded down over the side members of the other plate, said upper plate having a smooth surface provided with a plurality of goal 65 openings and an entrance aperture on the playing area, and means for guiding a spherical token from the lower plate to the playing area by passage through said entrance aperture, whereby the structure is adapted to be tilted to move the 70 token freely toward any goal through which the token is returned to the lower plate.

3. A game board comprising an upper plate having a flat unobstructed playing surface upon which a ball may freely move in all directions, 75 said plate provided with goal openings permitting

- the ball to pass through said plate, said plate also having an entrance aperture intermediate said goal openings and through which the ball is returned to the playing surface, a lower plate spaced 5 from said upper plate to receive the ball when passed through a goal opening, an inclined runway leading from the lower plate to a remote edge of the entrance aperture and extending towards one or more goal openings, and guides upon the 10 sides of said runway, whereby the ball when disposed upon the lower plate may be directed along said runway between said guides and through said entrance aperture to initiate a play upon the upper plate.
- 15 4. A game board comprising an upper plate having a flat unobstructed playing surface upon which a ball may freely move in all directions,
- said plate provided with goal openings permitting the ball to pass through said plate, said plate also having an entrance aperture intermediate said goal openings and through which the ball is returned to the playing surface, a lower plate spaced 5 from said upper plate to receive the ball when passed through a goal opening, an inclined runway leading from the lower plate to a remote edge of said entrance aperture and extending towards one or more goal openings, and guides upon 10 the sides of said runway and extending a distance upon said lower plate, whereby the ball when disposed upon the lower plate is directed by said guides to the runway and along said runway to and through said entrance aperture to initiate 15 a play upon the upper plate.

EARLE L. WHITEHALL.
